Primary Examiner — Amber R Stiles*Assistant Examiner* — Molly K. Orzechowski(74) *Attorney, Agent, or Firm* — Banner & Witcoff, Ltd.**CLAIM**

The ornamental design for a shoe as shown and described.

DESCRIPTION

FIG. 1 is a side view of a shoe showing my new design;

FIG. 2 is a front perspective view thereof;

FIG. 3 is a front view thereof;

FIG. 4 is an opposite side front perspective view thereof;

FIG. 5 is an opposite side view thereof; and,

FIG. 6 is a top view thereof.

The uneven-length broken lines immediately adjacent to the front center and rear ends of the shaded stripe define the bounds of the claimed design and form no part thereof. The even-length broken lines within the shaded stripe represent seams that form no part of the claimed design. The uneven-length broken lines depicting the remainder of the shoe form no part of the claimed design.
